his Attorney.

UNITED STATES PATENT OFFICE.

CARL WILSON SLUSSER, OF CHICAGO, ILLINOIS.

MEDICAL INSTRUMENT.

Application filed April 21, 1927. Serial No. 185,372.

My invention relates to a medical instrument, and more particularly to an instrument especially designed and adapted for cleansing the cervix and cervical canal and administering cervical and uterine medication.

The object of my invention is to provide an instrument of the above indicated character which is simple in construction, economical, safe and sanitary and particularly efficient in operation.

This application is in part a continuation of my pending application, Serial No. 159,411, filed January 6, 1927, of which the subject matter is reserved and incorporated in this present application.

My invention will be best understood by reference to the accompanying drawing forming a part of this specification, and in which,

Figure 1 is a vertical sectional view of a medical instrument incorporating my invention.

Figure 2 is a horizontal sectional view taken on approximately the line 2—2 of Figure 1.

Figure 3 is a fragmentary top plan view of my invention with the bulb removed and,

Figure 4 is a vertical plan view of a tapered valve or stop cock used in my invention.

In the drawings and for the purpose of illustration I have shown the preferred embodiment of my invention, in which 5 represents a soft rubber bulb, which has an opening 6 and a neck 7 adapted to be expanded for engagement over the corrugated end 8 of a hard rubber tube 9 which has a tapered end portion 10 adapted to fit in the conical opening 11 of an extension 12 on the body portion 13.

The conical opening 11 leads into a tubular opening 14 which leads to a cylindrical chamber 15 in the body 13. The cylindrical chamber 15 is accessible from the outside of the body portion 13, through a threaded opening 16 which is normally closed by a plug nut 17 having screw thread engagement therein; said nut 17 is provided with a flange 18 adapted to engage a shoulder 19 for limiting the inward movement of said nut and for making a leak proof closure for said opening 16. A rib member 20 is provided on said nut for engagement by the

thumb and finger for rotating said nut when so desired. The body portion 13 is provided with outwardly extending flared portions 21, as shown in Figures 2 and 3, which together with the main body portion form an enlarged flat base 22 on which the instrument may be stood when not in use.

The cylindrical chamber 15 leads into a conical chamber 23 which in turn leads into a long tubular opening 24 extending through the vaginal staff 25. The extreme end of said staff 25 is formed into a cup shaped member 26 which is provided with an approximately cylindrical opening 27 of proper size for receiving the cervix therein; said opening 27 tapers to approximately 70 conical shape where it joins the opening 24.

At the bottom and in one side of the cup member 26, is provided a depression or secretion receiving portion 28 as shown in Figure 1. Downwardly through the body 13 is provided a tapered bore 29 which passes through and is larger than the opening 24. Said tapered bore is provided with a similarly tapered plug 30 which acts as a stop cock or valve for the opening 24, by means 80 of the opening 31 which is adapted to register with the opening 24 for allowing the passage of fluid therethrough. The opening 31 is elliptical in form for permitting the member 30 to be moved downwardly through the bore 29 as it wears. The opening 29 and the member 30 are ground to fit thus eliminating unnecessary valve parts, and this construction makes it easy to take apart and clean and avoids germ collecting portions.

A thumb hold 32 is provided on the upper end of the plug member 30, for turning the same. Said thumb hold is short at one side as at 33 and longer on the other side as at 34. The shorter side 33 is adapted to be oscillated within the curved portion 35 of the shield 36 for permitting openings 24 and 31 to register and when the opening 30 is oscillated to a position at right angles to the opening 24 for making a fluid tight seal 100 of said opening 24, the longer portion 34 of said thumb hold contacts the shoulder 37 and thereby assuring the operator that the valve is properly and completely closed.

The staff 25 is made of such a length that the cervix may be received in the cup 26 and the body portion is wide in the direction of the bore 29, for providing shoulders 38 and

39 which make it impossible to accidentally insert the instrument too far and injure the patient. The member 36 in addition to providing a stop for the rotation of the valve, 5 also acts as a shield to prevent the said thumb hold coming in contact with the patient's body which would prevent the free operation of the thumb hold. Said staff and body parts are integral as shown, and 10 may be made of glass or hard rubber or similar rigid and sanitary materials.

In operation, the staff 25, with the bulb removed and the valve open, is inserted into the vagina, and positioned for receiving the 15 cervix into the cup 26. The tube 9, is then inserted into the opening 11, with the bulb compressed. The bulb is then allowed to slowly expand and thereby create a partial vacuum and thus drawing the cervix snugly 20 into a central and symmetrical position in the cup and allowing pus or other secretions to flow into the depression 28 out of the way of the medicated fluid to be introduced. The valve is then closed thereby holding the cervix in this position, and the tube 9 is removed from the opening 11. Medicated fluid is drawn into the bulb 5, the tube 9 again inserted into the opening 11, valve 25 opened, and the bulb compressed which 30 forces medicine directly into the cervical canal and on adjacent parts.

In case it is desired to administer powder instead of a medicated liquid, the nut 17 may be removed and the powder placed therein 35 and the nut replaced, and when the valve is opened, the powder may be forced up the passageway 24 to the cervix by air from the bulb 5 combined with suction of the vacuum in the cup and passageway 24.

40 While I have described my invention in its preferred form it is capable of variation without departing from the spirit of the invention. I do not, therefore, wish to be limited to the precise details of construction 45 set forth but desire to avail myself of such variations and modifications as come within the scope of the appended claims.

I claim as my invention:

1. A device of the class described comprising a body member having a vaginal staff thereon; means on the end of said staff for receiving the cervix; a passageway from said means through said staff; means for creating a vacuum therein; valve means for 50 closing said passageway and means for introducing medicine through said passageway.

2. A device of the class described comprising a body member; a vaginal staff integral therewith; a cup on the end of said staff for receiving the cervix; means in one side of said cup into which secretions may 55 flow; a passageway from said cup through said staff and body; valve means in said 60 passageway for closing the same; means for

creating a vacuum in said passageway, and means for introducing medicine through said passageway to said cup.

3. A device of the class described comprising a body member having a vaginal staff thereon; means on the end of said staff for receiving the cervix; a passageway from said cup through said staff; means for creating a vacuum therein; valve means for closing said passageway and means for introducing medicine through said passageway; a chamber in said body portion adapted 70 to receive medicine therein, and means for closing one end of said chamber. 75

4. A device of the class described comprising a body member; a vaginal staff integral therewith; a cup on the end of said staff for receiving the cervix; means in one side of said cup into which secretions may flow; a passageway from said cup through said staff and body; valve means in said 80 passageway for closing the same; means for creating a vacuum in said passageway, and means for introducing medicine through said passageway to said cup; a chamber in 85 said body portion adapted to receive medicine therein, and means for closing one end of said chamber. 90

5. A device of the class described comprising a body member having a vaginal staff thereon; means on the end of said staff for receiving the cervix; a passageway from said cup through said staff; means for creating a vacuum therein; valve means for closing 95 said passageway and means for introducing medicine through said passageway; a thumb hold on said valve for rotating the same, and means for limiting the rotation of said valve. 100

6. A device of the class described comprising a body member; a vaginal staff integral therewith; a cup on the end of said staff for receiving the cervix; means in one side of said cup into which secretions may flow; a passageway from said cup through said staff 105 and body; valve means in said passageway for closing the same; said passageway adapted to have a vacuum produced therein; and means for introducing medicine through said passageway to said cup; a thumb hold on 110 said valve for rotating the same; means for limiting the rotation of said valve; means for preventing said thumb hold coming in contact with the patient's body. 115

7. A device of the class described comprising a body member having a vaginal staff thereon; means on the end of said staff for receiving the cervix; a passageway from said cup through said staff adapted to have a vacuum created therein; valve means for closing said passageway and means for introducing medicine through said passageway; shoulders on said body portion for limiting the insertion of said instrument; a thumb hold on said valve for rotating the 120 125 130

- same; a guard member on said body member for preventing said thumb hold coming in contact with the patient's body, said guard member having edges thereon for limiting the movement of said thumb hold. 8. A device of the class described comprising a body member; a vaginal staff integral therewith; a cup on the end of said staff for receiving the cervix; means in one side 10 of said cup into which secretions may flow; a passageway from said cup through said staff and body; valve means in said passageway for closing the same; said passageway adapted to have a vacuum produced therein; 15 and means for introducing medicine through said passageway to said cup; an extension on said body member having an opening therein for receiving a vacuum producing and medicine injecting means therein. 20 9. A device of the class described comprising a body member; a vaginal staff integral therewith; a cup on the end of said staff for receiving the cervix; means in one side 25 of said cup into which secretions may flow; a passageway from said cup through said staff and body; valve means in said passageway for closing the same; said passageway adapted to have a vacuum produced therein; and means for introducing medicine 30 through said passageway to said cup; an extension on said body member having an opening therein for receiving a vacuum producing and medicine injecting means therein; shoulders on said body portion for limiting the insertion of said instrument; a thumb hold on said valve for rotating the same; a guard member on said body member for preventing the thumb hold coming in contact with the patient's body, said 35 guard member having edges thereon for limiting the movement of said thumb hold. 10. A device of the class described comprising a body member having a vaginal staff thereon; means on the end of said staff 40 for receiving the cervix; a passageway from said cup through said staff adapted to have a vacuum created therein; valve means for closing said passageway and means for introducing medicine through said passageway; a chamber in said body portion adapted to receive medicine therein, and means for closing one end of said chamber; shoulders on said body portion for limiting the insertion of said instrument; a thumb hold on said valve for rotating the same; means for limiting the rotation of said valve; a guard member on said body member for preventing the thumb hold coming in contact with the patient's body, said guard member having edges thereon for limiting the movement of said thumb hold. 45 50 55 60 65 70 75 80 85

11. A device of the class described comprising a body member; a vaginal staff integral therewith; a cup on the end of said staff for receiving the cervix; means in one side of said cup into which secretions may flow; a passageway from said cup through said staff and body; valve means in said passageway for closing the same; said passageway adapted to have a vacuum produced therein; and means for introducing medicine through said passageway to said cup; a chamber in said body portion adapted to receive medicine therein, and means for closing one end of said chamber; shoulders on said body portion for limiting the insertion of said instrument; a thumb hold on said valve for rotating the same; means for limiting the rotation of said valve; a guard member on said body member for preventing the thumb hold coming in contact with the patient's body, said guard member having edges thereon for limiting the movement of said thumb hold.

In testimony whereof I have signed my name to this specification.

CARL WILSON SLUSSER.
